DESIGN FOR A FLUORESCENT LAMP FIXTURE

Orrick H. Biggs, Beverly, and Charles F. MacCarthy, Salem, Mass., assignors to Hygrade Sylvania Corporation, Salem, Mass., a corporation of Massachusetts

Application November 8, 1939, Serial No. 88,126

Term of patent 14 years

To all whom it may concern:

Be it known that we, Orrick H. Biggs, and Charles F. MacCarthy, citizens of the United States, residing, respectively, at Beverly and at Salem, in the county of Essex and State of Massachusetts, have invented a new, original, and ornamental Design for a Fluorescent Lamp Fixture, of which the following is a specification, reference being had to the accompanying drawing, forming part thereof.

Figure 1 is a perspective view of a fluorescent lamp fixture embodying my new design, the other side being the same as the side shown.

We claim:

The ornamental design for a fluorescent lamp fixture, as shown and described.

ORRICK H. BIGGS.
CHARLES F. MACCARTHY.
